UNITED STATES PATENT OFFICE

151,724

DESIGN FOR A SERVICE STATION

Lysander T. White, New York, N. Y., assignor to
Cities Service Oil Company, New York, N. Y.,
a corporation of Pennsylvania

Application January 22, 1947, Serial No. 136,313

Term of patent 14 years

(Cl. D13—1)

To all whom it may concern:

Be it known that I, Lysander T. White, a citizen of the United States of America, residing in New York, in the county of New York and State of New York, have invented a new, original, and ornamental Design for a Service Station, of which the following is a specification, reference being had to the accompanying drawing, forming a part thereof.

Fig. 1 is a top plan view of a service station, showing my new design;

Fig. 2 is a side elevation, the opposite side presenting the same appearance; and

Figs. 3 and 4 are elevations of the left and right

hand ends of the station as shown in Figs. 1 and 2.

I claim:

The ornamental design for a service station, as shown and described.

LYSANDER T. WHITE.
